UNITED STATES PATENT OFFICE.

FRED A. BUCK, OF HUBBARDSTON, MICHIGAN.

STOVE.

No. 826,308.

Specification of Letters Patent.

Patented July 17, 1906.

Application filed May 27, 1905. Serial No. 262,700.

To all whom it may concern:

Be it known that I, FRED A. BUCK, a citizen of the United States, residing at Hubbardston, in the county of Ionia and State of Michigan, have made certain new and useful Improvements in Stoves, of which the following is a specification.

My invention is an improvement in stoves; and it consists in certain novel constructions and combinations of parts hereinafter described and claimed.

In the drawings, Figure 1 is a front perspective view of my invention, partly broken away. Fig. 2 is a similar view from the side. Fig. 3 is a transverse vertical section. Fig. 4 is a perspective view from the rear. Fig. 5 is a detail perspective of one of the check-drafts, and Fig. 6 is a detail view of the elbow-lever.

In the practical application of my invention, I provide a stove comprising a casing A, composed of the body portion a, a base a', and a top a². Within the stove I arrange a lining a³, cut away at the front, as at a⁴, and extending to within a short distance from the top of the stove.

The lining is spaced away from the front and rear walls of the stove and from the bottom thereof to form an upright front flue b, an upright rear flue b', and a base-flue b². Above the cut-away portion of the front lining is a smoke-consuming chamber B, closed at the rear by a baffle-plate b³ and communicating with the front flue and the fire-chamber at its bottom and at its top with the open space above the lining. The front and rear flues communicate below with the base-flue, and the rear flue communicates above with a smoke-vent b⁴; a damper b⁵ being arranged within the rear flue and adapted to swing forward to close the communication between the open space above the lining and the smoke-vent or to swing backward to close the rear flue.

An ash-pan C is supported above the base-flue on the inner face of the lining, and journaled thereabove in the walls of the stove is a shaft D, having secured thereto a revolving grate d. The grate may be revolved by any suitable means, as in the present instance by segment-gears d' d², secured to the shaft D and to a counter-shaft d³, journaled adjacent to the grate-shaft and provided with a portion d⁴, extending beyond the walls of the stove for engagement by a shaker.

A fire-pot E of the form shown in Fig. 1 is

supported above the grate and is provided with a flaring upper edge e and a dentated lower edge e'. The flaring edge of the pot slopes gradually inward, leaving no projection to catch ashes or cinders, and is of a contour conforming with that of the stove.

A smoke-consuming flue F is supported above the front edge of the fire-pot, the free edge of the baffle-plate connecting therewith and closing the opening thereabove. The smoke-consuming flue is of the shape shown in Figs. 1 and 3, having the flaring ends f and the perforations f' in its rear side and bottom.

Above the fire-pot and to the rear of the baffle-plate is a magazine G, provided with a sliding cover g, having secured thereto a rod g', projecting beyond the casing for manipulating the cover.

A coal-hopper H is arranged above the upper opening of the magazine and is provided with a hinged cover h, having secured thereto an elbow-lever h' of the form shown in Fig. 6 of the drawings and adapted to be engaged by a swinging cover h² to open the hinged cover. The swinging cover h² is pivoted to the top of the stove, as at h³, and when swung upon the pivot the front edge of the cover will engage the elbow-lever, thus turning the cover h upon its hinges.

Check-drafts K are arranged in openings a⁰ in the front and rear flues in an opening leading to the smoke-consuming flue and in an opening in the ash-door and comprise each a disk k², attached centrally by a pin k³ to a bar k, secured to the inner face of the casing. A cross-piece k⁴, rigid with the pin, engages, when the disk is turned, oppositely-disposed cams k' integral with the bar k and projecting rearwardly therefrom. A handle k⁵ is secured to the outer face of the disk for convenience in manipulating the same.

An ash-door L is arranged within an opening at the front of the stove for convenience in removing the ash-pan, and above the fire-pot at the side of the stove is arranged a poker-door M for convenience in stirring the fire. A soot-door N is arranged in an opening in the casing at the rear end of the base-flue, and on the front of the stove, below the check-draft of the front flue, is a grated door O, provided with mica plates. At the rear corners of the stove I arrange air-flues a^x on either side of the rear flue and passing entirely through the stove. These flues increase the radiating capacity of the stove, since they

draw cold air from beneath the stove, heat the same, and pass it up through the upper opening.

In operation the damper b^5 is lowered to close communication between the rear flue and the smoke-vent while the fire is being kindled, making a direct draft from the fire-pot through the smoke-consuming chamber into the smoke-vent. When the fire is well kindled, the direct draft may be shut off by raising the damper to close the communication between the upper part of the stove and the smoke-vent, thus forcing the heated gases downwardly through the front flue, the base-flue, and upwardly through the rear flue. The draft in either direction may be regulated by the check-drafts. The magazine being tightly covered, all the draft must be through the opening between the baffle-plate and the front lining-section.

The smoke-consuming flue is an efficient addition to the heating capacity of the stove, since it utilizes a considerable quantity of gaseous fuel otherwise wasted. The smoke-consuming flue F communicates with the outer air by means of an opening through the casing, in which is arranged a check-draft K. When the check-draft is opened, the air enters through the flue, passing out through the perforations and driving the unconsumed gases back upon the fire.

Having thus described my invention, what I claim as new, and desire to secure by Letters Patent, is—

1. A base-burning stove, comprising a casing provided with upright air-flues at the rear corners thereof, extending through the casing, a smoke-consuming chamber at the upper front part of the casing, a base-flue, and upright front and rear draft-flues communicating at the bottom with the base-flue, the front flue communicating at its top with the smoke-consuming chamber, and the smoke-consuming chamber and the rear flue communicating with a smoke-vent opening in the casing, a damper in the rear flue, an ash-pan supported above the base-flue, a shaft journaled above the ash-pan in the walls of the casing, a revolving grate mounted on the shaft, a fire-pot supported by the grate and provided with a dentated lower edge, a smoke-consuming flue supported in the smoke-consuming chamber above the fire-pot, a magazine behind the smoke-consuming chamber, a sliding cover therefor, a rod secured thereto and projecting from the casing, a coal-hopper arranged in the casing above the magazine, a hinged cover therefor, an elbow-lever on the cover, a swinging cover pivoted to the casing and adapted to engage the elbow-lever, check-drafts for the front and rear flues arranged in openings in the casing, and comprising a bar secured to the casing across the opening and provided with oppositely-disposed cams on its rear face, a disk, a

pin connecting the disk to the cross-bar, a cross-arm on the pin for engaging the cam-faces, an ash-door in the front of the stove, a poker-door adjacent to the smoke-consuming flue, and a soot-door in the base-flue.

2. A base-burning stove, comprising a casing provided with upright air-flues at the corners thereof, and extending through the casing, a smoke-consuming chamber at its upper front part, a base-flue, and upright front and rear draft-flues communicating at the bottom with the base-flue, the front flue connecting at its top with the smoke-consuming chamber, and the smoke-consuming chamber and the rear flue communicating with a smoke-vent opening in the casing, an ash-pan supported above the base-flue, a revolving grate supported above the ash-pan, a fire-pot supported above the grate, a smoke-consuming flue supported in the smoke-consuming chamber above the fire-pot, a magazine behind the smoke-consuming chamber, a sliding cover therefor, means for sliding the cover, a coal-hopper arranged in the casing above the magazine, a hinged cover therefor, a swinging cover pivoted to the casing, means whereby the swinging cover may elevate the hinged cover, means whereby the draft may be directed through the base-flue or through the consuming-chamber, and check-drafts in the smoke-consuming chamber and in the rear flue.

3. A base-burning stove, comprising a casing provided with upright air-flues at the corners thereof, and extending through the casing, a smoke-consuming chamber at its upper front part, a base-flue, and upright front and rear draft-flues communicating at the bottom with the base-flue, the front flue connecting at its top with the smoke-consuming chamber, and the smoke-consuming chamber and the rear flue communicating with a smoke-vent opening in the casing, an ash-pan supported above the base-flue, a revolving grate supported above the ash-pan, a fire-pot supported above the grate, a smoke-consuming flue supported in the smoke-consuming chamber above the fire-pot, a magazine behind the smoke-consuming chamber, a sliding cover therefor, means for sliding the cover, a coal-hopper arranged in the casing above the magazine, a hinged cover therefor, a swinging cover pivoted to the casing, means whereby the swinging cover may elevate the hinged cover, and means whereby the draft may be directed through the base-flue or through the consuming-chamber.

4. A base-burning stove, comprising a casing provided with a smoke-consuming chamber at its upper front part, a base-flue, and upright front and rear draft-flues communicating at the bottom with the base-flue, the front flue communicating at the top with the smoke-consuming chamber, and the smoke-consuming chamber and the rear flue com-

communicating with a smoke-vent opening in the casing, a revolving grate supported above the base-flue, a fire-pot supported above the grate, a smoke-consuming flue supported in the smoke-consuming chamber above the fire-pot, a magazine behind the smoke-consuming chamber, means for closing the upper opening of the magazine, a coal-hopper arranged in the casing above the magazine, a hinged cover therefor, a swinging cover pivoted to the casing, means whereby the swinging outer cover may actuate the hinged cover, and means whereby the draft may be directed through the base-flue or through the smoke-consuming chamber.

5. A base-burning stove, comprising a casing provided with upright air-flues at the corners thereof extending through the casing, a smoke-consuming chamber at its upper front 10 part, a base-flue, and upright front and rear

draft-flues communicating at the bottom with the base-flue, the smoke-flue communicating at its top with the smoke-consuming chamber, and the smoke-consuming chamber and the rear flue communicating with a smoke-vent in the casing, a revolving grate supported in the casing, a fire-pot supported above the grate, a smoke-consuming flue supported in the smoke-consuming chamber above the fire-pot, a magazine above the fire-pot, means for closing the upper opening of the magazine, a hopper above the magazine, means for closing the upper opening of the hopper, and means for directing the draft upwardly through the smoke-consuming chamber or downwardly through the base-flue.
